PROCESS AND APPARATUS FOR THE VACUUM DISTILLATION OF HYDROCARBONS

Filed Feb. 2, 1924

UNITED STATES PATENT OFFICE.

JOHN C. BLACK, OF DESTREHAN, LOUISIANA.

PROCESS AND APPARATUS FOR THE VACUUM DISTILLATION OF HYDROCARBONS.

Application filed February 2, 1924. Serial No. 690,206.

My invention relates to a process and apparatus for the vacuum distillation of hydrocarbons and more particularly for the manufacture of lubricating oil distillate and residual products.

Distillation under vacuum has several very marked advantages over distillation carried on under atmospheric or super atmospheric pressure.

10 One of the advantages is the reduced temperatures at which the distillates will distill, that is to say, their boiling points are reduced, and this becomes more marked as the vacuum is increased as, for instance, in the 15 lubricating oil fractions the normal boiling points may be reduced as much as 150° F. or more when a vacuum of 24 to 26 inches of mercury below atmospheric pressure is maintained on the oils under distillation.

20 The direct effect of the lowered boiling point is very evident when it is considered that the valuable lubricating oils have a normal boiling point of well over 600° F. and as high as 750° F. and over and by distilling 25 under sufficient vacuum such oils will distill at approximately 600° F., this fact has a very important bearing on the quality and yield of the lubricating fractions for the reason that they will crack very readily when heated 30 to a temperature of 625° F. and over and very rapidly indeed at 700° F. to 725° F., the effect of such cracking is to produce low boiling low viscosity products and carbonaceous material with resulting loss of yield of 35 the desirable high viscosity high boiling point oils. From this it will be seen that if the temperature of the distilling oil is kept at around 600° F. or under that, practically no cracking and consequent loss of the lubricating oils will result. This is equally true in 40 distilling for residual products such as when making high boiling point reduced distillates or in the manufacture of asphalt.

The effect of the vacuum is to reduce the 45 vapor pressure of the oils and under high vacuum the yield of lubricating fractions may be increased to as much as double or more compared to distillation under substantially the normal pressure of the atmosphere. It is 50 well-known in the art that the cracking point of an oil is not always correspondingly reduced with the lowering of its boiling point, for example, an oil having a boiling point of 725 degrees F. may start to slightly crack 55 at 650 degrees F., while at 725 degrees F. the

velocity of the cracking reaction would be very materially increased. Therefore, if the vapor pressure is sufficiently reduced to lower the boiling point to approximately 600 degrees F., substantially no cracking will take 60 place and a distillate would be recovered without any substantial alterations due to cracking, thereby increasing the yield of high boiling stock such as lubricating oil, from a given amount of petroleum oil.

65 Heretofore the usual practice in the manufacture of lubricating oil distillates and residual products under vacuum where the batch method is employed is to introduce the oil to be distilled or reduced into a cylindrical still (or in a series of stills in the continuous method), the stills being set over a fire box for direct heating, this type of construction, however, has several very serious drawbacks, especially when large capacity is required. In vacuum distillation in cylindrical stills it is essential to heavily brace the shell against a collapsing pressure and especially so the bottom or fire sheet which is 70 subject to high heat with resultant softening 75 of the steel and collapsing of the bottom will take place unless thoroughly braced, but bracing the bottom presents the difficulty of additional metal in the fire sheet wherever the bracing occurs with consequent overheating 80 of the plate at that point and eventually burning 85 of the steel. This action is hastened by the accumulation of carbonaceous material between the bracing members and the shell and which is difficult to keep clean due to 90 the close proximity of the shell and braces. Furthermore, a still of this type requires frequent shutdowns for cleaning, due to accumulations of coke building up on the braces and bottom steam lines which result in "hot spots" 95 which, if allowed to persist, would cause distortion of the fire sheet and possible rupture, requiring renewal of the plate. Also a still of the above type is very largely limited in 100 its capacity to produce distillates by the amount of its heating surface, whereas, in the type to be later described, the heating surface may be greatly extended, practically to any amount desired within the limits of the evaporator and condensing equipment, 105 thereby effecting a very great saving in first cost of construction and in subsequent operation.

I am aware that stills of somewhat similar design and construction are used in the crack- 110

ing of oils to produce gasoline or naphtha products, such stills or evaporators do not require bracing against a collapsing pressure, as they are operated at a pressure higher than 5 the atmosphere, furthermore, they are used for a different purpose and would require modification to be applicable to vacuum distillation. For this reason, I believe my process and apparatus is new in the art to which it 10 applies.

In the accompanying drawing I have indicated an advantageous form of apparatus, the drawing in part being diagrammatic.

Referring to the drawing, 1 represents a 15 still or evaporator which may be constructed in a horizontal or vertical position. I prefer the horizontal position when thermal circulation is used or when ejector circulation is used; it is also applicable to pump circulation, but when the latter is used, I prefer the 20 vertical type as it lends itself to easier operation. The shell of the still or evaporator is braced with circular or longitudinal braces or a combination of both, but for convenience 25 of drawing, I show outside circumferential bracing of the shell, the heads are concave, the latter may be convex if desired, but would require internal bracing if used. The bracing is designated as 3 in the drawing and is 30 shown as an I-beam. This bracing may be used either on the outside of the still as shown or on the inside. I prefer the outside bracing as this permits a clear inside shell easily kept 35 clean and accessible, and is more easily and cheaply constructed. This type of construction is one of the advantages of my apparatus, as outside bracing would not be practical on a shell fired still. The vertical type of evaporator could be either circumferentially or 40 vertically braced, depending upon engineering expedient. 10 on the drawing is a tray to facilitate evaporation, but which is not essential to the process, in the vertical type this tray would be displaced by perforated trays 45 down over which the incoming oil would percolate. 41 designates a bottom perforated steam line and 42 a top steam supply inlet pipe. The steam supplying these steam lines is preferably superheated, but is not necessarily 50 essential to the process as any dry steam supply is sufficient. 4 are suspension connections for holding the evaporator in place. 5 are flanged connections to which the drop 55 pipes 6 are connected. 7 is an ejector, either of the liquid jet type, steam or gas type. 8 is a heating coil made up of tubes in series. 9 shows the discharge pipes from the heating coil 8 which discharges onto the tray 10; 11 is the furnace for heating the coil 8; 12 is an 60 arch to cause the proper flow of combustion gases. 13 is the stack to carry away the products of combustion. 14 is the vapor line connecting the still to the tower 16; 15 is a separating chamber fitted with a tight bottom 65 37, and a top hooded opening 35. 36 is a baf-

fling material and may be tile or stone, or it can be fitted with baffle plates or trays; this is immaterial. 17 is a vapor pipe connecting the tower 16 to the condenser 18. 19 is a look-box. 20 is a pipe connecting the look-box 19 70 to the auxiliary separator or receiver 21, 22 is a vacuum connection from the separator 21 to the lower portion of the tower 16 below the diaphragm 37, and which is designated 38. 23 is a vacuum pipe and is connected to the 75 vacuum pump 47. 24 is a connection from pipe 23 to the receiver 38 and is fitted with a valve 24'. The pipe 25 connects the lower portion of the top section of the fractionating tower 16 through the pipe 44 to the lower section of the fractionating tower designated by the numeral 38, passing through a cooler 26 controlled by a valve 25'. 27 is a runback pipe from the separator 15 to the evaporator 1 and is fitted with a trap 27'; 28 is a pump 80 for discharging separator 21 through pipe 49 and valve 49' and discharges through pipe 33 and valve 33' to tank 34. 29 is a pump connected to the receiver 38 through pipe 39 and valve 39' and discharges through pipe 30 and valve 30' to the top of the tower 16 and into 85 a spray 40. The pump 29 is also fitted with a discharge pipe 31 and valve 31' into tank 32 or into other tanks as, for instance, tank 32'. 90

In the drawing the apparatus is shown for batch operation and is chosen for its simplicity. Substantially the same construction, however, can be used for continuous operation by installing the usual cross-over connections usual in that method of operation, for instance, the continuous flow lines would be connected from one evaporator to the other and the charging oil would be fed into the first evaporator. Also the drawing shows the circulation of the oil through the 100 tubes to be actuated by a steam pump 7. This can be replaced by the substitution of a pump taking suction on the drop leg 6 and discharging into the heating tubes at the point where ejector 7 is shown. The heating coil 110 or element is shown in the drawing as a single continuous coil and is so shown for simplicity. However, the heating element may be made up of a group of such heating coils in multiple, thereby providing a very 115 large heating surface. In fact it may be made double the heating surface of a shell still of equal charging capacity. Another advantage of the tubular heating element for vacuum distillation is the small size of the tubes 120 which are sufficiently strong in themselves to withstand the collapsing pressure of the vacuum without any internal bracing as is the case where large shell type fire stills are employed. Pump 28 has a branch connection 43 125 and valve 43' discharging into pipe 30 so that the condensate from condenser 18 may be circulated through tower 16 to permit of sifting out any heavy fractions that might be desirable in the tower condensate, the lighter por- 130

tions again being vaporized to again pass over into condenser 18, the increment in this condensate being discharged into tank 34.

There is also a connection 44 and valve 44' 5 to permit the tower condensate to run back to the still 1 if so desired. If more than one still is used in a series of stills, then this connection 44 may also connect to the next still in advance, thereby obtaining a redistillation 10 of the primary distillate. This is often found desirable. 45 is a residuum drawoff connection and 46 is a charging line with a valve 46'. 47 is a vacuum pump with a connection 48 to the vacuum header 23.

15 Having now described my apparatus, I will describe its operation in the manufacture of paraffine distillate.

The crude paraffine distillate carrying stock is charged into the evaporator 1 to its 20 normal charging capacity, say, eight hundred to one thousand barrels or more, the oil fills the heating coil or element 8 through the drop pipes 6. Heat is now applied to the coils in the furnace 11; the oil in the coils becomes heated and, due to its lessened density, 25 will rise through the tubes 9 and discharge onto the tray 10. Fresh oil downflowing through the pipes 6 will take its place and thus thermal circulation will be created. 30 This can be continued for some time or until the oil in the evaporator has attained a temperature above the boiling point of water, steam or other propelling medium may now be turned into the ejector 7 and more rapid 35 circulation will result and also more rapid heating of the oil. I prefer to use steam in the ejector as it is easy to apply, will serve to promote distillation in the evaporator, and has the advantage of condensing out in the 40 coil 18, thereby reducing the volume of gases to be handled by the vacuum pump as would be the case if permanent gases were to be used for this purpose.

If there are any low boiling fractions 45 present in the oil, they will begin to distill over passing out of the still through vapor pipe 14 into the separator 15, tower 16, vapor pipe 17, and condenser 18 to the look-box 19, rundown line 20, separator 21, thence by 50 pump 28 and discharged for disposal elsewhere. When the temperature has reached 350° F., in the evaporator, then the valve 24' in pipe 24 may be gradually opened, so that the air, gases and vapors in the system may 55 be exhausted through the pipe 23 connected to the vacuum pump 47 through pipe 48. This will result in increased vaporization of the oil in the evaporator. More heat is continually applied and the heavier or so 60 called paraffine fractions will now commence to vaporize. If these were allowed to pass through the tower 16 and be condensed in condenser 18 along with the steam used in circulation and evaporation, then a heavy difficultly separated emulsion would result.

Now, to prevent this, I circulate, by means of the pump 29, a portion of the paraffine distillate condensed in tower 16 and collected in the receiver 38 through pipe 25 and cooler 26, discharging it through pipe 30 and valve 30' 70 to the top of the tower 16 through the spray pipe 40. This has the result, if properly regulated, of condensing the heavier high boiling point and high viscosity distillates in the tower 16 from whence they run to the receiver 38 to be pumped away or partially recirculated. In this way, the lighter distillates and the steam are permitted to pass over into the condenser 18 and separately disposed of. By this procedure, the heavier high boiling point and higher viscosity oils are separated at a temperature above the boiling point of water from the lower boiling point oils and from the water which remains in the form of steam. These lighter oils and steam 85 form the residual vapors that pass into the condenser 18 and from there independently disposed of as previously described. In this manner, the tower condensate is a clean practically water-free distillate, the water being 90 separately condensed and disposed of, thereby eliminating the troublesome emulsions, as will be the result if one single condensate is made from an unseparated vapor, and which is condensed in one operation. 95

The circulation of the tower condensate may be so regulated that it will eliminate the rerunning or reducing operation by permitting the lighter low viscosity low-boiling point oils to pass over to the condenser 18, 100 and condensing out the heavier high boiling high viscosity oils desired in a reduced distillate.

This equipment is equally well adapted for reducing paraffine distillates where the residual product in the evaporator is the desirable fraction and by proper handling of the injection oil in the tower, an intermediate paraffine distillate may be obtained therefrom and the lighter fractions and the water vapor 110 will pass over into the condenser 18. This type of still is well adapted to the manufacture of asphalt and at the same time also called paraffine distillate may be produced in the tower 16, the asphalt remaining in the 115 evaporator as a residual product.

Having now described my process and apparatus for vacuum distillation, what I claim as new and useful is:

1. A process for the production under reduced pressure of a reduced lubricating oil stock, and the separation of an intermediate distillate and lower boiling hydrocarbons and water, from a mixture of the same, wherein the reducing and distilling operation is effected under a partial vacuum greater than 24 inches of mercury, which comprises, circulating the mixture of hydrocarbons through heating tubes and an evaporator, heating a portion of said hydrocarbons to a 130

vaporizing temperature and introducing steam therein, maintaining a reduced pressure on the evaporator sufficient to prevent decomposing or cracking of the hydrocarbons, vaporizing the lower boiling hydrocarbons and passing the same together with the introduced steam into a fractionating tower, under reduced pressure, contacting said hydrocarbon vapors and steam in counter-current flow with a previously condensed portion of said intermediate distillate at a temperature sufficient to condense and extract from said mixture of hydrocarbon vapors and steam, substantially all the intermediate distillate free from water and substantially free from low boiling hydrocarbons, and separately condensing and collecting said lower boiling hydrocarbons and water.

20 2: An apparatus for the vacuum distillation of oil, which comprises, a coil adapted

to be heated, an evaporator, means for circulating oil from the bottom of said evaporator through said coil and back onto a pan in said evaporator, external bracing provided for said evaporator of sufficient strength to withstand a reduced atmospheric pressure greater than 24 inches of mercury without the employment of internal bracing, a fractionating tower connected to said evaporator, means for cyclicly circulating oil through said fractionating tower, a cooler connected to the lower portion of said fractionating tower, a condenser connected to the upper portion of said fractionating tower and means for producing a vacuum in said distillation, fractionation and condensing system.

In testimony whereof I hereunto affix my signature.

JOHN C. BLACK.
